GARMENT.

1,214,483.

Specification of Letters Patent. Patented Jan. 30, 1917.

Application filed May 27, 1916. Serial No. 100,176.

To all whom it may concern:

Be it known that I, LOUIS STRAUSS, a subject of the Czar of Russia, and a resident of the city of New York, borough of Brooklyn, in the county of Kings and State of New York, have invented a new and Improved Garment, of which the following is a full, clear, and exact description.

Among the principal objects which the present invention has in view are: to provide a garment with a collar which may be converted at will into a head covering; to provide a garment with a cape collar which may be converted into a military or standing collar; and to provide a garment with a collar of the character mentioned which will lie smoothly on the shoulders to be worn as a cape.

Drawings.—Figure 1 is a view of a garment having a collar constructed and arranged in accordance with the present invention, showing the collar disposed as a head covering; Fig. 2 is a view of the same, showing the collar outspread to disclose the fastening devices with which it is furnished; Fig. 3 is a view of a sweater having a collar disposed as a cape; Fig. 4 is a view of the same showing the collar disposed in the form of a military collar; Fig. 5 is a view of the same, showing the collar disposed as a high-throated cape collar.

Description.—As seen in the drawings, a knitted sweater is provided with a collar 10. The collar 10 is made in the form generally known as cape or wide-spreading collars, on the normally under side whereof are mounted tabs 11 and 12. The tab 11 is secured preferably by sewing the same to the collar 10 adjacent the outer edge thereof. When the collar is worn in either the positions shown in Figs. 3 and 4 of the drawings, the tab 11 is held in the position shown in Fig. 2, by means of a button 13, which is engaged by a buttonhole loop formed adjacent the free edge of the tab.

At the opposite sides of the collar and adjacent the edge thereof, are buttons 14, said buttons being employed for holding the tab 11 in the position shown best in Fig. 1. When the tab 11 is thus disposed, it will be noted that the two halves of the long edge of the collar are held juxtaposed to form a head covering for the wearer. The rear end of the gap between the edges is closed by folding the material at that point and securing the

same in position by engaging the button 15 with the buttonhole loop 16.

To adjust the collar 10 in the position shown in Fig. 1 of the drawings, the collar is raised after the sweater is adjusted to the body, and the half sections of the edge are folded the one on the other. The tab is released from engagement with the button 13, and is carried across the head and folded across the lapped edges of the half sections of the collar. The buttonholes 16 and 17 with which the tab 11 is provided, are then engaged with the buttons 14 and 15. It will now be found that any opening between the juxtaposed edges of the half sections of the collar is closed and that the collar and flap form a complete head covering for the wearer.

In Fig. 4 of the drawings, the tab 12 is shown in active position, the buttonhole in the free end of said tab being engaged by a retaining button 18. Also it will be observed that the collar 10 has been folded partially inside the sweater, so that the exposed portion forms a standing or military collar for which the tab 12 provides a throat latch of conventional character.

In Fig. 2 of the drawings, the tab 12 is shown in the inactive position in which it is retained by a button 19. This is the normal position for the tab 12 when the collar 10 is disposed as a cape collar, as shown in Fig. 3 of the drawings.

It will be noted that the tab 11 is shaped, the free edge being bowed, as shown best in Figs. 1 and 2 of the drawings. This arrangement permits the collar to mold or conform to the shape of the head of the wearer, and results in the head covering resting more snugly when in service.

Claims:

1. A garment having a cape collar, the length of said collar approximating the height of the head of the wearer; means mounted on said collar for temporarily connecting the juxtaposed edges thereof in service; and means for temporarily connecting the juxtaposed edges of sections of said collar when lifted to envelop the head of the wearer, said means comprising a tab having a buttonhole at the free end thereof, said tab being secured to said collar at the under side thereof when worn as a cape, said tab being adapted for extension across the juxtaposed edge sections of oppositely disposed collar 110.

- sections to form in conjunction therewith a hood-like covering, and a button secured to the opposite section of said collar for engaging in service the buttonhole in said tab.
- 5 2. A garment having a cape collar, the length of said collar approximating the height of the head of the wearer; means mounted on said collar for temporarily connecting the juxtaposed edges thereof in service; and means for temporarily connecting the juxtaposed edges of sections of said collar when lifted to envelop the head of the wearer, said means comprising a flap having a series of buttonholes at the free end thereof, said flap being secured to said collar at
- 10 the under side thereof when worn as a cape, said flap being adapted for extension across the juxtaposed edge sections of oppositely-disposed collar sections for forming in conjunction therewith a hood-like covering, and 20 a series of buttons secured to the opposite section of said collar for engaging in service the series of buttonholes in said flap.
- 15 In testimony whereof I have signed my name to this specification in the presence of 25 a subscribing witness.

LOUIS STRAUSS.
